UNITED STATES PATENT OFFICE

ALBERT H. CHALMERS, OF FAIRVIEW, BIRMINGHAM, ALABAMA

COKE-OVEN-PUSHER CONTROL

Application filed June 5, 1928. Serial No. 282,943.

This invention relates to coke ovens and aims to provide improved control apparatus so arranged that the operator on the pusher side of the oven can only actuate the pusher ram for the purpose of discharging the coke after the door on the discharge side of the oven has been opened.

Heretofore various electrically actuated mechanisms involving complex circuits and interlock systems have been proposed. In practice, such electrical devices have been extremely troublesome and their operation is seriously interfered with by the falling coke, the rising flames on the discharge side of the oven and the heat and dust on the pusher side to make it almost impossible to properly keep the electrical devices in operative condition. My invention aims to overcome these deficiencies of the prior practice and to provide an extremely simplified yet reliable means for preventing the actuation of the pusher ram until the operator on the discharge side of the oven is prepared to have the coke ejected.

The invention will be fully apparent from the following specification when read in connection with the accompanying drawings and will be defined with particularity in the appended claims. In the drawings—

Fig. 1 is an elevation partly in transverse section showing a conventional form of coke oven and pusher machine equipped with control apparatus embodying the invention;

Fig. 2 is a plan of a portion of a battery of ovens, one oven chamber and part of another being shown in horizontal section;

Fig. 3 is an enlarged view showing certain of the main operating elements;

Fig. 4 is a plan of certain of the parts shown in Fig. 3;

Fig. 5 is a detail section of a control valve.

Referring in detail to the drawings, 10 represents a conventional type of coke oven structure as a whole which includes a plurality of oven chambers 12 which extend transversely from the pusher side 14 to the discharge side 16. The chambers 12 are closed on the pusher side by means of doors 18 and on the discharge side by means of similar doors 20. The usual form of larry charging car 22 trav-

els over the top of the oven structure and is adapted to charge the fuel to the oven chambers 12 through suitable openings 24.

The oven is heated in the usual manner and further description will be omitted as the heating apparatus and control therefor forms no part of the invention.

On the pusher side of the oven, a pusher machine indicated generally at 26 travels on a track 28 and is propelled by means of a motor 30 driven by current supplied from the conductor rails 32, the motor being connected by suitable cables 34 and 36 with a controller 38.

The pusher machine 26 carries a pusher ram 40 of standard construction arranged to be actuated by a pusher motor 42 and suitable intermediate transmission mechanism of known construction not shown. The motor 42 is under control of a controller 44 and the supply of current of the motor and controller from the conductor rails 32 through conductor cable 34 is under control of a switch indicated generally at 46 which is arranged to be actuated by means of compressed air as will hereinafter appear.

The pusher machine also carries a door lifting member 48 which is actuated by a motor 50 connected to a suitable controller 52. The member 48 carries mechanism of known construction including mechanically actuated hooks 54 adapted to engage extensions 56 on door 18. The hooks 54 are actuated by a motor 58 connected to a controller 60. By proper manipulation of the controller 52 and controller 60, the pusher machine operator can remove the door 18 preparatory to actuation of the pusher ram 40. The pusher machine is also provided with a levelling bar 49 adapted to be actuated by a motor 51 under control of controller 53.

It is of utmost importance that the pusher ram 40 is only actuated after the door 20 on the discharge side 16 of the oven has been removed, otherwise, serious damage will be done to the coke oven structure. On the discharge side 16 of the oven structure, a known type of door operating machine 62 is provided which carries mechanism of known 100

construction indicated at 64 for removing the doors 20.

In normal operation, the doors on opposite ends of any particular oven chamber 12 are removed and the load discharged. It is customary to work on a regular operating schedule so that the ovens are pushed in a regular sequence but the adjacent ovens are not pushed consecutively. Therefore, considerable care must be exercised by the operators of the pusher machine 26 and the door operating machine 62 so that the pushing schedule is strictly adhered to. The normal operation of coke pushing machines as heretofore practiced is intended to be as follows: The operator of the door machine 62 by means of the mechanism 64 removes the door 20 on the discharge side of the coke oven. After this is done, the operator of the pusher machine 26 removes the door 18 by means of the door operating member 48 and hook mechanism 54, it being understood that the doors 18 and 20 which are moved are intended to be those closing the opposite ends of the same oven chamber 12. The operator of the pusher machine 26 then causes the pusher machine to travel along on the tracks 28 a short distance in order to align the pusher ram 40 with the oven chamber whose doors have just been removed. The ram 40 is then caused to travel forward through the oven chamber 12 so as to eject the coke which falls into a suitable car not shown.

The ram 40 is then returned to its retracted position and the doors 18 and 20 are replaced and the emptied oven chamber 12 is charged with coal by the larry car 22 through openings 24. This coal is levelled by means of the levelling bar 49 which operates through a suitable opening formed in the door 18. After a given oven chamber is thus worked, the respective operators of the pusher machine 26 and the door operating machine 62 are supposed to move their machines to the next oven on the pushing schedule and repeat the above described operation.

There is a chance, however, that the operator on the pusher machine may remove a door which does not correspond with the oven door removed by the operator of the machine 62 of the discharge side of the oven, and the pusher operator not realizing the error may cause the ram 40 to travel with the result that the coke will be pushed against an unremoved door 20. Such an error causes serious damage because of the pressure exerted on the oven structure by the powerful ram 40.

Various means, mostly electric, have been devised for preventing pushing of coke until after the door on the discharge side has been removed but such means in practical operation are readily rendered inoperative or ex-

tremely inefficient by the extreme heat of the coke ovens or by accumulations of dust and the action of flame escaping from the oven structure.

My improved control apparatus includes rugged and reliable means whereby the operation of the ram 40 is under control of the door machine operator located on the discharge side 16 of the oven structure.

My apparatus includes a cylinder 66 carried by the pusher machine and having therein a piston 68, the rod 70 of which is arranged to actuate the switch 46 having blades 72 which coact with switch contacts 74 and 76 connected, respectively, with the conductors 78 and 80 leading to the controller 44 and supply wires 34. A counter-weighted bell-crank 82 pivoted at 84 has a pin slot connection 86 with a rod 88 also connected with piston 68. Normally, this weighted bell-crank tends to hold the switch blades 72 out of engagement with the contacts 74 and 76. When fluid pressure is supplied to the cylinder 66, piston 68 is moved to the position indicated in Fig. 3 so as to engage the blades 72 with the contacts 74 and 76 and thus complete the circuit between the current supply 34 and the motor 42 through controller 44.

The cylinder 66 has connected therewith a flexible hose 90 which terminates in a coupling member 92 adapted to be engaged with a similar coupling member 94 secured to the end of a pipe 96. There is a separate pipe 96 for each oven chamber of the battery of ovens and each pipe extends upwardly between the buckstays 100 of the oven and then across the top as indicated at 102. On the discharge side of the oven, each pipe 102 is connected with a downwardly extending pipe 104 having a control valve 106 therein. Each control valve 106 connects by means of a pipe 108 with a compressed air or other fluid pressure main 110.

The main 110 extends longitudinally of the oven battery on the discharge side 16. Each control valve 106 is a three-way valve having a plug 112 which when turned to the position of Fig. 5 will permit compressed air or other suitable fluid pressure to flow from pipe 110 to the connections described across the top of the oven by way of the pipes 102 and 96 to the cylinder 66 so as to move the piston 68 and switch blade 72 to the closed position of Fig. 3. When the control valve plug 112 of Fig. 5 is turned clockwise through an angle of 90 degrees, the counter-weighted arm 82 will pull the blades 72 to the right and break the motor circuit and the air from cylinder 66 will be discharged through port 114 of the valve 106. With the arrangement described, it will be appreciated the operation of pusher ram 40 is under control of the operator of the door machine located on the discharge side 16 of the oven,

thus there is no chance of the pusher machine operator inadvertently actuating the ram to push the coke from an oven whose discharge door 20 has not been previously removed by the operator of the door removing machine 62.

It is clear that in normal operation, the pusher machine operator successively connects the coupling member 92 of the flexible 10 hose with the members 94 of the different ovens listed on the operating schedule, but if he makes an error and connects the hose to the wrong coupling 94, no damage can be done for the supply of fluid pressure for 15 actuating the pusher ram will not be available, it being remembered that the door machine operator on the discharge side 16 only makes the air supply available for the particular oven chamber which has had its door 20 removed. If desired, each control-valve 25 106 may be automatically actuated by the movement of the door machine or by the movement of the door actuating mechanism 64, thus making the operation practically foolproof.

While I have described quite specifically the details of the embodiment of the invention illustrated, it is not to be construed that I am limited thereto since various modifications and substitution of equivalents may be made without departing from the invention as defined in the appended claims.

What I claim is:

1. The combination with a coke oven structure including a battery of coke ovens and a pusher machine movable along one side thereof, a pusher ram and a motor for actuating it carried by said pusher machine, compressed air actuated switch for controlling said motor and means located on the side of the structure opposite that on which the pusher machine moves for controlling the supply of compressed air to said switch.

2. The combination with a coke oven structure including a battery of coke ovens and a pusher machine movable along one side thereof, a pusher ram and a motor for actuating it carried by said pusher machine, a switch controlling the supply of current to said motor, a cylinder and a fluid pressure actuated piston therein operatively connected with said switch and a valve located on the side of the oven structure remote from the pusher for controlling the supply of fluid pressure to said cylinder.

3. The combination with a coke oven structure including a battery of coke ovens and a pusher machine movable along one side thereof, a pusher ram and a motor for actuating it carried by said pusher machine, current supply means for said motor, a switch between said current supply means and said motor, a fluid pressure actuated device for moving said switch and a valve for controlling the supply of fluid to said device from

the side of the oven remote from the pusher machine.

4. The combination with a coke oven structure including a battery of coke ovens and a pusher machine movable along one side thereof, a pusher ram and a motor for actuating it carried by said pusher machine, current supply means for said motor and a switch between said current supply means and said motor, a fluid pressure actuated device operatively connected to said switch, a fluid conduit extending across the oven structure, disconnectible means for establishing communication between the conduit and said fluid pressure actuated device, a main supplying fluid to conduit, and a control valve located on the side of the oven structure remote from the pusher machine in said conduit.

In witness whereof, I have hereunto signed my name.

ALBERT H. CHALMERS.
